UNITED STATES PATENT OFFICE.

CHARLES T. MURRAY, OF KANSAS CITY, MISSOURI.

STEAM-GENERATOR.

SPECIFICATION forming part of Letters Patent No. 605,895, dated June 21, 1898.

Application filed September 10, 1897. Serial No. 651,194. (No model.)

To all whom it may concern:

Be it known that I, CHARLES T. MURRAY, of Kansas City, Jackson county, Missouri, have invented certain new and useful Improvements in Steam-Generators, of which the following is a full, clear, and exact description, reference being had to the accompanying drawings, forming a part thereof.

My invention relates to steam-generators, 10 and more particularly to a steam-generator for use in connection with stereotype-tables; and it consists in certain novel and peculiar features of construction and combinations of parts, as will be hereinafter described and 15 claimed.

The object of the invention is to produce a generator of the character above mentioned which is of knockdown and portable construction, so that its parts may be easily and 20 quickly assembled together in operative relation to a stereotype-table, and which is simple, strong, durable, and comparatively inexpensive of construction.

In order that the invention may be fully 25 understood, I will proceed to describe it with reference to the accompanying drawings, in which—

Figure 1 represents a vertical central section of a steam-generator embodying my invention and also shows in elevation a portion 30 of a stereotype-table of the customary construction. Fig. 2 is a horizontal section taken on the line II II of Fig. 1. Fig. 3 is a horizontal section of the mixing-chamber and air-controlling-valve mechanism. Fig. 4 is a vertical section taken on the line IV IV of Fig. 3.

In the said drawings, 1 designates a cylinder, preferably of sheet metal. 2 designates a circular base-plate upon which said cylinder 40 rests and by which it is embraced.

3 designates a circular top plate closing the upper end of the cylinder.

4 designates a cylinder or tube which is arranged centrally of the cylinder 1 and is 45 screwed at its lower end into a cap 5, occupying a hole in the bottom plate 2, and provided with a horizontal flange or shoulder 5^a, which rests upon said bottom plate and thereby supports the tube 4. Screwed upon and closing 50 the upper end of said tube is a cap 6, and said

cap fits snugly in an opening in the top plate 3 and is provided with a shoulder or flange 6^a, which bears against the under side of said top plate and thereby is held reliably in position. The bottom and top plates 2 and 3, respectively, are clamped firmly against the opposite ends of the cylinder 1 by means of tie-bolts 7 and nuts 8, engaging their opposite ends, as shown.

In order that the water contained in the 60 generating-tube 4 may be more quickly converted into steam, said tube is provided with a plurality of U-shaped pipes 9, which communicate at their ends, in different horizontal planes preferably, with the tube 4, in order 65 to provide numerous passages through which the water may circulate and because of being thus divided or segregated be more quickly raised in temperature.

10 designates an outlet-pipe for the steam. It communicates with the upper end of the tube 4 through the cap 6 preferably, and at its upper end with one chamber or compartment of the stereotype-table. A second outlet-pipe 11 also communicates with the upper 75 end of the tube 4, and at its upper end communicates with the second chamber or compartment of the stereotype-table.

12 designates the return-pipes for the steam or condensation thereof. These pipes communicate at their upper ends with the chambers or compartments of the table hereinbefore referred to and at their lower ends communicate with the generating-tube 4, just above the burner, in order that the temperature of the water returning through said pipes 80 may be more quickly raised.

13 designates a gage of the customary construction which communicates at its upper end with the pipe 11 and at its lower end 90 with one of the pipes 12.

14 designates an annular pan or trough wherein the combustible mixture of gas and air is contained. Said annular pan or trough rests upon the bottom plate 2 and snugly 95 surrounds the tube 4. It is provided with a burner-cap 15, provided with a large number of burner-openings 16, from which the flame shoots upward and impinges upon and envelops the return-pipes 12 and the pipes 9 of 100

the generating-tube 4. At one side the pan or trough is provided with a tubular offset 17, and fitting upon the same and projecting through the cylinder 1 is a tube 18, which in 5 practice is the mixing-chamber of the device.

19 designates an approximately hemispherical perforated cap which is secured at the outer end of the mixing-chamber, and 20 designates a valve-casing which extends longitudinally of and projects centrally through said cap and into the mixing-chamber. At its inner end said casing terminates in the nozzle 21, forming an inlet-valve seat, and controlling the passage of gas through said 15 nozzle is a needle-valve 22 of the customary form.

23 designates a supply-pipe which communicates with the valve-casing at one end and at its opposite end with any suitable gas- 20 supply. (Not shown.)

24 designates a draft-regulating cap mounted rotatably upon the valve-casing 20. This is of hemispherical form and fits snugly upon the similarly-formed cap 19 and is provided 25 at intervals with openings 25, which may be caused, by the proper adjustment of the draft-regulating cap, to expose more or less of the openings of the cap 19 and thereby permit of an increased or diminished volume of 30 air passing into the mixing-chamber.

In practice after the generator is properly assembled with relation to the stereotype-table, as shown in Fig. 1, and is supplied with the proper quantity of water the valve 22 is 35 manipulated to permit of the passage of gas under pressure through the mixing-chamber and into the pan or trough 14. The cap 24 is also manipulated to expose more or less of the openings of the cap 19 in order that the 40 suctional action exerted by the discharge of the gas into and through the mixing-chamber may draw a sufficient volume of air into the mixing-chamber and thence into the pan or trough 14, by which time the gas and air are 45 thoroughly commingled and are in the nature of a combustible gas, which escapes through the burner-cap 15 and is ignited by the introduction of a lighted match or taper through a door-opening 26, formed in the cylinder 1, 50 and closed normally by a sliding plate 27. The flame and heat from this circular burner-cap envelop and impinge partly upon the tube 4 and pipes 9, and as a consequence the water is quickly generated into steam, which 55 escapes by way of the pipes 10 and 11 to the stereotype-table and returns with its temperature lowered or as condensed steam back to the generating-tube by way of the pipes 12, as will be readily understood. This circulation 60 is continuous as long as the burner is in

operation and water is contained within the tube.

The flame and heat of course may be regulated by the volume of gas and air and by the quality of the gas, determined, of course, by 65 properly proportioning the volume of each discharged or admitted into the mixing-chamber.

If it is desired to move the generator independent of the table, it is only necessary to uncouple the pipes 10, 11, and 12 from the 70 table, and if it is desirable to ship the generator it may be done with the parts in operative position, because it is of compact construction, or by removing the pipes 10, 11, and 12 and the nuts 8 from the upper ends of 75 the tie-rods the generator may be quickly and easily taken apart.

From the above description it will be apparent that I have produced a steam-generator for stereotype-tables which embodies 80 the features of advantage enumerated in the statement of invention, and it is to be understood, of course, that changes which do not involve a departure from the principle of construction involved may be resorted to. 85

Having thus described the invention, what I claim as new, and desire to secure by Letters Patent, is—

1. A steam-generator, comprising a cylinder, a top and a bottom plate clamped thereon, a cap stepped into the bottom plate, a cap stepped into the top plate, a generating-tube screwed into and closed by said caps and arranged centrally of the cylinder, pipes communicating with said tube and projecting laterally therefrom, outlet and inlet pipes communicating with the upper and lower end of the tube, respectively, and a burner surrounding said tube and resting upon the bottom plate of the cylinder, substantially as 100 described.

2. A steam-generator, comprising a cylinder, a top and a bottom plate clamped thereon, a cap stepped into the bottom plate, a cap stepped into the top plate, a generating-tube 105 screwed into and closed by said caps and arranged centrally of the cylinder, pipes communicating with said tube and projecting laterally therefrom, outlet and inlet pipes communicating with the upper and lower ends of 110 the tube, respectively, a gas-burner, and a valve controlling the passage of gas into said burner, substantially as described.

In testimony whereof I affix my signature in the presence of two witnesses.

CHARLES T. MURRAY.
